UNITED STATES PATENT OFFICE.

THEODORE F. TAYLOR, OF CHICAGO, ILLINOIS.

AUTOMATIC TELEGRAPH.

SPECIFICATION forming part of Letters Patent No. 293,110, dated February 5, 1884.

Application filed April 14, 1883. (No model.)

To all whom it may concern:

Be it known that I, THEODORE F. TAYLOR, a citizen of the United States, and a resident of Chicago, in the county of Cook and State of Illinois, have invented certain new and useful Improvements in Automatic Telegraphs, of which the following is a specification.

The object of my invention is to provide means for insuring that the characters, which, in an automatic telegraph system, are usually formed upon chemically-prepared paper by the agency of electric currents transmitted from a distant station, shall be clearly defined and of uniform distinctness, which I effect by a peculiar organization of batteries and circuits, as hereinafter explained.

The invention consists in combining with the usual transmitting and receiving devices of an automatic, and more particularly of a chemical, telegraph an auxiliary battery having an electro-motive force less than that of the main transmitting-battery, and of reverse polarity thereto, and two branch conductors containing artificial resistances extending to the earth from points in the main line near the transmitting and receiving terminals thereof, respectively. The auxiliary or opposing battery is placed in the same circuit with the transmitting-battery, and the currents which are transmitted from the latter through the receiving-instrument reach the earth by passing directly through the opposing battery. The circuit of the auxiliary battery is permanently completed, independently of the transmitting apparatus, through both branch conductors and artificial resistances.

It is well known that in fast-speed automatic telegraphs, especially when electro-chemical receivers are employed, it is difficult to cause the rapidly-succeeding impulses to be recorded in characters sufficiently distinct and sharply defined to render the dispatch perfectly legible. This difficulty is due to the fact that an electric impulse, especially when transmitted through a conductor of great length, becomes prolonged as to its duration, and the character which is recorded thereby, instead of being a sharply-defined dot or dash, is correspondingly lengthened out, and becomes faint at its commencement and termination, while its intermediate portion is comparative-

ly distinct. The action of the auxiliary battery at the receiving-station is to normally maintain upon the main line a continuous electric current of negative polarity, which will not produce a mark upon the chemical paper. When the transmitting-battery is applied thereto, the excessive electro-motive force of the latter overpowers the current from the auxiliary battery, and exerts, by means of a positive current, an electro-chemical action upon the chemical receiving-paper, producing a mark. Immediately upon the interruption of the circuit of the transmitting-battery the unopposed current from the auxiliary battery at the receiving-station flows back through the paper and into the main line, thereby both neutralizing the residual or inductive current which tends to flow through the receiving-instrument, and serving to clear the main line from electro-static charge.

The accompanying drawing is a diagram illustrating one method of carrying out my invention.

Referring to this diagram, A and B respectively represent a transmitting and a receiving station of an automatic telegraph. These stations are united, in the usual manner, by a main line, L. At the transmitting-station A is placed a transmitting-battery, E, having its positive pole connected by a conductor, 2, with the metallic transmitting-drum T. The negative pole of the battery E is connected with the earth at G by a conductor, 1. A metallic transmitting-stylus, t, rests upon the surface of the drum T, and any well-known or suitable mechanism may be employed for causing an automatic transmitting pattern-slip, P, to pass between the stylus and the drum. The transmitting or pattern slip P is perforated with groups of apertures of varying lengths and intervals, as required, to represent the dispatch which it is desired to transmit by an arbitrary system of signs—such, for example, as the Morse telegraphic code.

At the receiving-station B is placed a recording apparatus, M, of any suitable or well-known construction. A strip of chemically-prepared paper, N, is caused to pass rapidly and uniformly between the drum M' and the stylus m of this instrument in a well-known manner. The drum M' is connected with the

earth by conductors 4 and 3, between which is placed the auxiliary battery E', the positive or marking pole of this battery being connected with the drum and the negative pole with the earth. The electro-motive force of the battery E' is preferably made about one-third as great as that of the battery E.

Extending from a point, o, in the main line, near the transmitting-station, to the earth at 10 G is a branch conductor, l, containing an adjustable artificial resistance, R. A similar conductor, l', extends from a point, o', near the receiving terminal of the line L, to the conductor 3, in which an artificial resistance, 15 R', is also included, this resistance being preferably approximately equal to the resistance R. The proportions of the resistance of the main line and the artificial resistances which I prefer to employ may be approximately indicated as follows: Assuming the resistance of 20 the main line to be nine hundred ohms, the resistances R and R' should be each about three thousand ohms. The main battery E should then comprise about ninety cells and the auxiliary battery E' thirty cells.

The operation of my improved system is as follows: While the apparatus is at rest a constant current from the battery E' traverses the line L and the branch conductors l and l', dividing itself between them in inverse proportion to their respective resistances, in accordance with the well-known law of Ohm. When the transmitting pattern-strip P is caused to pass between the roller T and the stylus t, 35 electric impulses will be transmitted upon the line L from the positive pole of the battery E, which will traverse the main line L, the two branch lines l and l', and their included resistances, and also the receiving-instrument M. 40 The greater portion of this current will, however, on account of the less resistance offered, traverse the receiving-instrument M and the auxiliary battery E'. The current from the last-named battery will thus be neutralized 45 and overpowered, and the excess of current from the main battery E will act upon the chemically-prepared paper and record, in the form of dots and dashes or like arbitrary characters, the impulses which are transmitted.

50 Immediately upon the cessation of each impulse the auxiliary battery E' again acts to send an impulse of positive polarity through the receiving-paper and stylus in the reverse direction, and through the line L, which returns to the negative pole of the battery by way of the artificial resistances R and R'. Such an impulse, following immediately upon the interruption of the circuit of the transmitting-battery, acts to destroy the effect of the "tailoring" or static discharge of the line L upon the receiving-instrument, and also to neutralize the same throughout the line. By thus opposing the discharge of the line by a reverse current transmitted directly through the chemical paper, a sharply-defined record will in all 55 cases be obtained, and by transmitting the op-

posing impulse through the line the latter will be placed in a condition to receive the next succeeding impulse and to record the same as a sharply-defined character.

70

I have described my invention as organized for effecting the impressions by closing the circuit of the main battery E. It is evident, however, that the polarity of the two batteries may be reversed, the negative poles of each being then applied to the main line L, and the necessary electric changes produced by interrupting the circuit of the battery E. This may conveniently be accomplished by substituting for the perforated non-conducting strip 80 P suitable conducting material, upon the surface of which are formed arbitrary characters of non-conducting substance in the required sequence. The circuit of the battery E will in this case be normally complete, and will be 85 interrupted by the passage of a non-conducting surface between the drum and stylus of the transmitting apparatus. At the receiving-station the current from the battery E' will, so long as the battery E is applied to the line, 90 be overpowered and neutralized by the latter, and no effect will be produced upon the receiving-paper. When, however, the battery E is disconnected from the line, in the manner described, by the non-conducting surface constituting a dot, dash, or other telegraphic signal, the current from the battery E', traversing the conductors l' and l, will produce upon 95 the chemical paper a record corresponding to the duration of the interruption of the circuit. The current from the battery E' is immediately overpowered, when the battery E is again applied to the line in the same manner as in the organization first described.

95

I do not claim, broadly, the use of one or 100 more auxiliary batteries of reverse polarity and inferior electro-motive force, placed at one or more points in the main line between the transmitting and receiving stations, and acting in opposition to the pulsations from the 105 transmitting-instruments to free the main line from static electricity; nor do I claim the application of one or more secondary polarization or storage batteries between the transmitting and receiving stations for the same 110 purpose, as I am aware that such organizations have been heretofore known and used.

115

I claim as my invention—

1. The combination, substantially as hereinbefore set forth, of a telegraphic main line, 120 a main battery, means for transmitting electric impulses from said battery upon said main line, a telegraphic receiving-instrument, an opposing battery having less electro-motive force than said main battery, through which 125 the impulses transmitted from said main battery to the receiving-instrument are caused to pass, and two branch conductors, each containing an artificial resistance, permanently completing the circuit of the opposing battery 130 through the line and receiving-instrument.

125

2. The combination, substantially as here-

130

- inbefore set forth, of a main circuit, in which is placed a main battery, a transmitting-instrument, an opposing battery of less electro-motive force than the main battery, and a receiving-instrument, two branch or shunt conductors permanently united with the main circuit, one of which spans the transmitting-instrument and main battery and the other the receiving-instrument and opposing battery.
3. The combination, substantially as hereinbefore set forth, of a main circuit, in which is placed a main battery, a transmitting-instrument, an opposing battery of less electro-motive force than the main battery, and a receiving-instrument, two branch or shunt conductors permanently united with the main circuit, one of which spans the transmitting-instrument and main battery and the other the receiving-instrument and opposing battery, and an artificial resistance placed in each of said branch or shunt circuits.

4. The combination, substantially as hereinbefore set forth, of a main line, a main battery, means for transmitting electric impulses therefrom upon said main line, a chemical receiving-instrument, an auxiliary battery of reverse polarity placed in the line adjacent to the said receiving-instrument, a branch or shunt conductor permanently completing the circuit of said opposing battery through said receiving-instrument, and an artificial resistance included in said conductor. 25
- 30

In testimony whereof I have hereunto subscribed my name this 11th day of April, A. D. 1883.

THEODORE F. TAYLOR.
